UNITED STATES PATENT OFFICE.

HUGH SCOTT WINE, OF CLARKSBURG, WEST VIRGINIA.

RATCHET HYDRANT WRENCH.

Application filed March 22, 1921. Serial No. 454,481.

To all whom it may concern:

Be it known that I, HUGH S. WINE, of Clarksburg, county of Harrison, and State of West Virginia, a citizen of the United States, have invented certain new and useful Improvements in Ratchet Hydrant Wrenches, of which the following is a specification.

My invention relates to an improvement 10 in hydrant wrenches.

The object is to provide a simple tool adapted for use especially with hydrants.

This invention consists in the main of a handle fashioned at one end for coupling 15 and uncoupling hose and having a section cut away at the opposite end and made removable therefrom, both main and removable section counterpart structures and adapted to be dove-tailed and mortised and 20 tenoned together and having orifices formed therethrough and their inner faces counterbored and longitudinally grooved to receive a toothed wheel, having an opening through the center to receive a nut and a spring actuated ratchet plunger, fitted to and slidably mounted in the longitudinal groove 25 and adapted to cooperate with the toothed wheel.

In the accompanying drawings,

30 Figure 1 is an edge view.

Figure 2 is a view at right-angles to Figure 1 with the removable section removed.

Figure 3 is a view in perspective of the 35 removable section.

Figure 4 is a section on line 4-4 of Figure 1, and

Figure 5 is a section through the line 5-5 of Figure 2.

40 A represents the handle of the wrench with its end 1, fashioned to receive and turn an ordinary hose coupling it having a hole 2, therein to receive the usual stud on the coupling.

45 The opposite end of the wrench is cut transversely and longitudinally through the center as indicated by the line 3, in Figure 1, and the numeral 4 indicates the removable section which is substantially a counter-

50 part of the integral half section 6, and the two are dove-tailed together at the inner end 7, as shown in Figures 1, 2 and 3 and otherwise fitted throughout their lengths on their inner faces as shown in Figure 1.

55 Each section 4 and 6 is provided with an

orifice 8, therethrough and the ends are counterbored or countersunk as shown at 9, to receive the ratchet toothed wheel 10, the hubs 11, of which fit and turn in the orifices 8, as a bearing, the counterbore or 60 countersink 9, affording clearance for the teeth of the wheel 10, as shown in Figures 1 and 2.

Each section 4 and 6 is provided with a longitudinal groove 12, which when the 65 parts are together is approximately square or rectangular in cross section and the ratchet plunger 13, is fitted to slide but excluded from turning therein. The tail 14, of this plunger is preferably of smaller diameter 70 thus forming a shoulder 15, between which and the end 16, of the groove the spring 17, is confined. This spring normally forces the ratchet plunger against the teeth of the wheel 10, confining the movement of the 75 wheel to one direction not turning the wheel when swung in the opposite direction. In other words, by reason of this construction the ratchet plunger rides over the teeth freely when the handle is turned one way 80 and locks the handle to the wheel when turned in the opposite direction after the manner of other ratchet wrenches.

The angular slot 18, through the center is of any form, but as shown in Figure 2, 85 is hexagonal.

The sections 4 and 6 are held together by dowel pins 19, projecting from the inner face of one section and entering dowel holes 20, in the other section, as well as by means 90 of the dove-tailed inner ends 7, and by screws 21, which screw into the holes 22, threaded to receive them.

In this way I have provided a simple ratchet hydrant wrench, composed of few 95 parts, not easy to get out of order, but easily replaced if they do become impaired by simply unscrewing the screws 21, and separating the parts. The ratchet plunger, spring and toothed wheel are all shut in 100 and housed and only the ends of the hubs 11, are exposed.

The hose coupling end forms an extension of the handle and increased leverage for the ratchet wrench end and by its curve 105 indicates the direction in which the ratchet is to be turned and the ratchet wrench end constitutes an elongation of the handle and increased leverage for the hose coupling end, the whole presenting a neat and at- 110

tractive appearance with a general taper throughout its length as shown in Figure 1.

I claim,

A wrench including a handle, having one end cut out transversely and longitudinally through the center, and dove-tailed at the inner end, leaving an integral half section, removable counterpart half section having one beveled end which fits the dove-tailed inner end of the main section, each section having registering longitudinal grooves and countersunk orifices, as well as means for

fastening the sections together, a ratchet-toothed wheel journaled in the countersunk orifices and housed between the sections 15 when secured together, said wheel having an angular slot in the center to receive the article to be turned, and a sliding spring-actuated ratchet plunger located in the groove for locking the ratchet-toothed 20 wheel.

In testimony whereof I hereunto affix my signature.

HUGH SCOTT WINE.
